UNITED STATES PATENT OFFICE.

CHARLES STUART, OF PATERSON, NEW JERSEY.

MACHINE FOR LUSTERING SILK.

SPECIFICATION forming part of Letters Patent No. 705,716, dated July 29, 1902.

Application filed January 20, 1902. Serial No. 90,397. (No model.)

To all whom it may concern:

Be it known that I, CHARLES STUART, a citizen of the United States, residing at Paterson, in the county of Passaic and State of New Jersey, have invented certain new and useful Improvements in Machines for Increasing the Luster of Silk, of which the following is a specification, reference being had therein to the accompanying drawings.

My invention relates to a machine for increasing or intensifying the luster of silk; and the object of my improvements are, first, to provide a machine that will give to the silk fiber a permanent and more brilliant luster, which will be retained and shown in the finished fabric; second, to afford facilities for the treatment of a large quantity of fiber at one time; third, to reduce the cost of the treatment of silk fiber after it is dyed by saving in time and labor required in its preparation for manufacturing purposes; fourth, to produce a machine upon which the moistened fiber after it is dyed may be held and stretched and prevented from contracting while being submitted to a drying heat in a suitable room or compartment, so that the gradual drying will exert a strain upon the fiber until it is dry, after which it will not shrink. I attain these objects by the mechanism illustrated in the accompanying drawings.

As the mechanism shown is capable of many modifications which may be made in the construction of the machine without departing from the essential principles involved in my invention, I do not wish to limit myself strictly to the specific construction shown, and will hereinafter claim, broadly, a machine embodying such elements as the invention necessarily implies.

In the drawings similar letters of reference refer to like parts throughout both views.

Figure 1 is a side view of a machine embodying my invention; and Fig. 2 is a vertical section of a part of the same, showing the arrangement of the wet skeins of silk fiber and the stretching mechanism which prevents the fiber from shrinking while being dried or after it is dried.

The uprights A, braces a, cross-beams B, the long beams C, and the receiving-strips c constitute the framework of the machine.

On each side and near the bottom of the uprights A a suitable metallic side plate D is secured by screws d or otherwise and is reinforced by the inner plate d', which rests on shoulders cut in the uprights to receive it. A series of shafts I are journaled in bearings in the side pieces D and reinforcing-plates d', one end of each of said shafts having a portion i', reduced in size, forming a shoulder, as shown in Fig. 2, the end of the reduced portion passing through the side plates, as shown in said Fig. 2, where it is secured by a washer i² and a split pin i³. The other end of each of said shafts I is squared to fit a crank-lever O or a ratchet-lever O', as indicated by the letter i. On the operating end of each of said shafts I is secured a ratchet-wheel G, and a pawl H is secured to the outer side plate D—one for each of said ratchet-wheels G. The top receiving-strips c are provided with segmental notches c', adapted to receive and hold the uppermost rods E, each of which is capable of holding a number of skeins of silk or other fiber.

I do not wish to limit myself to rods of any particular material; but I prefer to use rods of hickory or other hard wood, glazed or enamelled, to prevent the fiber from catching or sticking. Each of the said rods is provided with circumferential grooves, one near each end thereof and one midway between the ends thereof to prevent the displacement of the links e and the S-shaped links e', which connect the upper and lower rods in vertical series, as shown, when they are filled with the skeins of silk or other fiber S. The links e connect the ends of the rods, and the links e' connect them at the center.

A chain F or other suitable device is secured to each of the shafts I by hook i⁴ or otherwise and is provided at its other end with a double S-shaped hook e², which engages the lowermost of the vertical series of horizontal rods E.

My stretching-machine is erected in a close room or compartment which is capable of being heated to a temperature of 120°. After the silk or other fiber is taken from the dye-bath it is put in a whiz to extract some of the moisture therefrom, and instead of putting it then into a dry-room until dry and then placing it in a small steam-stretcher where it

is enveloped in a bath of live steam, moistened, and stretched, I place it on my enameled rods, as shown in Fig. 2 of the drawings, as many skeins as the rods will hold, then stretch it by 5 the manipulation of the crank and ratchet-levers, run the temperature of my close room or compartment from 90° up to about 120° and leave the skeins there for three or four hours in that stretched condition. The skeins of 10 fiber are thus maintained in a stretched condition during the process of drying, as it is impossible for them to shrink, and when they are removed from my machine they are perfectly dry, do not shrink, and have a permanent and intensified luster which is retained 15 and exhibited when woven into a fabric.

With this description of my invention, what I claim, and desire to secure by Letters Patent, is—

- 20 1. In a machine for increasing the luster of silk, the combination of a frame, means for suspending therefrom a series of interdependent skeins of wet silk, flexible means connecting each series with a mechanism located in 25 the lower portion of the frame, and which is adapted to stretch the silk, and to maintain it in a stretched condition while being dried to prevent shrinkage, substantially as set forth.
2. In a device for increasing the luster of

silk, the combination of a frame, a series of 30 horizontal rods suitably connected and depending from said frame, said rods being adapted to hold skeins of silk stretched between each pair, flexible means connected to the lower portion of the frame, and to the 35 lowest rod of each series for stretching the wet skeins and for preventing the contraction of the same while drying, and ratchet means for holding the said flexible means, as set forth.

3. In a device for increasing the luster of 40 silk after it is dyed, the combination of a frame, horizontal rods suitably connected and depending from said frame, said rods being adapted to hold skeins of wet silk stretched 45 around each pair, flexible means connecting the lowest rod with a mechanism in the lower portion of the frame, and such a mechanism for stretching the wet skeins and for preventing the contraction thereof while drying, substantially as set forth.

In testimony whereof I affix my signature in presence of two witnesses.

CHARLES STUART.
